Phineas F. King & Enock Blasdel
Gentlemen

The subject is referred to in their Gentlemen's Patent and a marking part
of the same containing a description in the words of the late
Phineas F. King & Enock Blasdel themselves of their improve-
ment in the Fancy Card used in wool carding Machines

To all persons to whom these presents shall come. Be it known that
the Phineas F. King of Sparta Township and Enock Blasdel of
Lawrenceburg Township in the County of Dearborn & State of In-
diana have made an "improvement in the Fancy Card used in
wool carding Machines" and that the following is a description
of the same. The Carding Machine to which this improvement
is applied is constructed in every respect like those in common use.
This improvement which we claim as our invention is in the Fancy
Card for cleansing the main cylinder & doffer. Instead of the usual
Fancy Card (which is of short wire) the one we have invented & prefer-
red to use is made of needles or long steel pointed wire teeth properly
secured in leather behind by wire or any other suitable substance.

Our Fancy Card constructed of needles or long steel pointed wire teeth,
not only does the business of the common Fancy Card in a superior
manner, but it cleans the main cylinder & doffer without wearing
the cards, like the common fancy card. This improvement can
be applied to all wool carding Machines. The invention here
claimed is that of making Fancy Cards (as before described) of needles
or long steel pointed wire teeth made of common wire properly secured,
instead of the short pointed fancy cards now in use. In testifying
that the above is a full & true description of our invention we have
hereunto signed our names before two witnesses and made oath to
the same at the City of Washington this 12th day of December 1830.
